UNITED STATES PATENT OFFICE

PHILLIP RAFF, OF CHICAGO, ILLINOIS

DESIGN FOR A COMBINED LIGHTING AND AIR CIRCULATING FIXTURE

Application filed November 4, 1932. Serial No. 45,764. Term of patent 7 years.

To all whom it may concern:

Be it known that I, PHILLIP RAFF, a citizen of the United States, residing at Chicago, in the county of Cook and State of Illinois, have invented a new, original, and ornamental Design for Combined Lighting and Air Circulating Fixtures, of which the following is a specification, reference being had to the accompanying drawing, forming part thereof.

The figure is a side view of a combined lighting and air circulating fixture, showing my new design.

I claim:

The ornamental design for a combined lighting and air circulating fixture, as shown.

PHILLIP RAFF.
